UNITED STATES PATENT OFFICE.

JAMES H. GRAHAM, OF TORRINGTON, CONNECTICUT, ASSIGNOR TO SPLITDORF ELECTRICAL COMPANY, OF NEWARK, NEW JERSEY.

SPARK-PLUG.

1,200,607.

Specification of Letters Patent. Patented Oct. 10, 1916.

Application filed May 6, 1915. Serial No. 26,400.

To all whom it may concern:

Be it known that I, JAMES H. GRAHAM, a citizen of the United States, residing at Torrington, in the county of Litchfield and State of Connecticut, have invented certain new and useful Improvements in Spark-Plugs, of which the following is a specification.

My invention relates to improvements in a spark plug such as used for igniting charges in internal combustion engines.

One of the objects of my invention is to provide a spark plug, the parts of which when assembled will retain their relative position when subjected to the heat of the engine cylinders.

In some types of internal combustion engines, the cylinders get much hotter than in others, owing to the differences in the cooling system, construction of the engine cylinders and the manner of placing the spark plugs.

In the usual form of spark plug, the main insulator for the center electrode is held in position by means of a stuffing nut engaging the body or shell of the plug and drawing downward on the insulator against suitable gaskets. I have found in practice that in this type of construction, due to the expansion of the parts from the heat derived from the engine cylinders, the parts become loosened and misplaced by the vibration of the engine to such an extent that the spark plug is rendered useless.

My invention is directed to means for correcting these faults, at the same time keeping the number of parts reduced to a minimum and thereby providing a plug which is cheap to manufacture and easy to assemble.

One embodiment of my invention is shown in the drawing, wherein—

Figure 1 is an assembled view of my improved spark plug; Fig. 2 is a sectional view of Fig. 1; Fig. 3 is an assembled view of the center electrode, main insulator and stuffing nut; Fig. 4 is a plan view of the locking device used in the assembly of my plug; Fig. 5 is a side elevation of Fig. 4.

Referring now particularly to the details

in which like numerals refer to corresponding parts in the various figures, 1 is the body or shell of the plug, which is threaded at 2 for the purpose of being screwed into the cylinder walls of the engine.

3 illustrates one form of a ground electrode. The center electrode 4 is covered by an insulator 7, made of mica or other suitable material. One end of the electrode 4 has threads 18 and at the opposite end is shown an electrode point 5, securely fastened in the recess 6 of the electrode. The point 5 may be of special material or it can be integral with the main part of the electrode 4. 8 is a stuffing nut or gland having a chamfered part 21 and threads 19 at one end.

In the form shown, the center electrode is tapered from the threaded part to a point 22 near the opposite end. As the mica is wound onto the electrode, it bulges slightly at the point 22 thereby furnishing a pinching point 70 for the stuffing nut or gland 8 which is tapered internally to correspond to the taper on the center electrode 4, the mica being put on substantially uniform in thickness. Fig. 3 shows the insulator 7 and stuffing nut or gland 8 assembled on to the center electrode 4 before they are put into the plug, thereby forming a unitary structure of these parts.

The upper portion of the shell 1 is contracted or shouldered at 21 in a suitable manner to receive a gasket 9 of any well known type which is first dropped into place when the plug is to be assembled and then the integral structure just described and shown in Fig. 3 is passed through the shell 85 of the plug and a locking device, shown as a lock washer 10 is then put into position over the top of the electrode 4 and insulator 7. The lock nut 11 is then put into position and turned as tightly as possible.

The locking device 10 is preferably made of steel and given a spring temper and has an opening 20 between the limbs which are offset as shown in Fig. 5 so that when the locking nut 11 is drawn up, the limbs of the locking device 10 engage the shell 1 and the locking nut 11, in such a manner as to take up any expansion there may be between

these parts due to heat, thereby holding the stuffing nut or gland 8 securely against the gasket 9, preventing any leakage of gases out of the plug. After the parts, just described, have been assembled, to the shell, the washer 12 carrying a gasket 13 is put into position, followed by the outside insulator 14 and the washer 15. A lock-washer 16 is then put over the threaded end of the electrode and the nut 17 screwed into position, thereby putting a constant strain on the tapered electrode which insures a tight fit with the stuffing nut or gland 8.

It will be noted that the nut 18 is adapted to take a particular form of terminal, yet it will be understood that any type of nut or nuts may be used to receive the various styles of terminals. After the assembly of the plug has been completed in the manner as outlined above, the ground electrode 3 is then put into place.

While I have shown my invention applied to one particular form of plug, it will be apparent to anyone skilled in the art that numerous changes and alterations may be made without departing from the spirit of the invention or the scope of the appended claims.

Having thus described my invention, what I claim is—

1. In a spark plug, the combination of a shell having a central hole contracted at the top, a gasket adapted to lie within the contracted portion, a central electrode and an insulator therefor, a stuffing gland adapted to engage said insulator and said gasket, a locking nut adapted to engage the end of said stuffing gland and a locking device between said shell and said locking nut.
2. In a spark plug, the combination of a shell having a central hole contracted at the top, a gasket adapted to lie within the contracted portion, a central electrode having an insulator and a stuffing gland mounted thereon as a unitary structure, said gland being threaded and chamfered at one end to receive a locking nut and to engage said gasket and a locking device between said lock nut and said shell.
3. In a spark plug, the combination of a shell having a central bore of substantially uniform diameter but having a shoulder at one end of said bore, a gasket adapted to engage said shoulder, a central electrode, a main insulator for said electrode, a stuffing gland fastened to said insulator and adapted to hold said insulator and electrode within the shell, a locking nut for said gland to draw the insulator, electrode and gland into working relation with the shell and a locking device between the lock nut and the shell.
4. In a spark plug, the combination of a shell having a bore with an inner shoulder at one end, a gasket to engage said shoulder, a center electrode having a sparking point at one end and threaded at the other and being tapered between the ends, insulating material mounted on the tapered part of said electrode, a stuffing gland internally tapered to correspond with the taper on said electrode and mounted on the insulating material, said gland being externally threaded at one end and chamfered below the threaded portion to engage said gasket, a locking nut to engage the threaded part of said gland and a locking device between said lock nut and the shell.
5. In a spark plug, the combination of a shell having a central bore with an inner shoulder at one end, a gasket adapted to engage said shoulder, a unitary electrode structure, consisting of a metallic center, carrying a sparking point, an insulator and a stuffing gland, said unitary structure adapted to go within said shell, a locking nut outside said shell to engage the stuffing gland to hold the unitary electrode structure in working position against said gasket in the shell and a locking device between the lock nut and the shell for the purpose described.
6. In a spark plug, the combination of a shell having a central bore contracted at one end, a gasket adapted to fit within the contracted part, a tapered central electrode threaded at one end and having a sparking point at the other, an insulator mounted on the electrode, a stuffing gland mounted on the insulator, a lock nut outside the shell and adapted to engage the stuffing nut to draw the same against said gasket, a locking device between the lock nut and the shell, a cupped washer above the lock nut, a gasket within said cupped washer, a secondary insulator resting on said second mentioned gasket and within the cupped washer and means for locking said secondary insulator to the shell of the plug.
7. In a spark plug, the combination of a shell having a central bore contracted at one end, a gasket adapted to fit within the contracted part, a tapered central electrode threaded at one end and having a sparking point at the other, an insulator mounted on the electrode, a stuffing gland mounted on the insulator, a lock nut outside the shell and adapted to engage the stuffing nut to draw the same against said gasket, a locking device between the lock nut and the shell, a cupped washer above the lock nut, a gasket within said cupped washer, a secondary insulator resting on said second mentioned gasket and within the cupped washer and means for locking said secondary insulator to the shell of the plug, and means for putting a constant tension between the center electrode and the stuffing gland.
8. In a spark plug, the combination of a

shell having a central bore contracted at one end, a gasket adapted to fit within the contracted part, a central electrode and an insulator therefor, means for supporting said electrode and insulator within said shell, said means extending outside said shell and adapted to be engaged by fastening means

to hold said parts in working position in the shell and a locking device between said fastening means and said shell.

10

In testimony whereof, I affix my signature.

JAMES H. GRAHAM.
